DRAIN CULVERT

Filed Feb. 19, 1930

INVENTOR,
BY *Arthur R. Hutton*
Borrell & Borrell
ATTORNEYS.

UNITED STATES PATENT OFFICE

ARTHUR R. HUTTON, OF BERKELEY, CALIFORNIA, ASSIGNOR TO CALIFORNIA CORRUGATED CULVERT CO., OF BERKELEY, CALIFORNIA, A CORPORATION OF CALIFORNIA

DRAIN CULVERT

Application filed February 19, 1930. Serial No. 429,576.

The present invention relates to drain culverts for the protection of earth fills or embankments.

In the construction of fills or embankments, especially those for highways, it is necessary to provide suitable drains to carry off rain water falling upon the top of the fill, in order to prevent erosion of the sides thereof.

10 The principal object of the present invention is to provide an inexpensive structure which can be easily installed at the upper edge of a highway or other fill to collect and carry off rain water falling upon its top.

15 Other objects are to provide a drain culvert having sufficient flexibility to withstand the usual settling of a new fill and sufficient strength to prevent destruction from accidental contact of vehicles moving along the highway. Still further objects are to provide a drain culvert which will not materially damage the wheels of a vehicle accidentally striking it; which is protected against the entrance of leaves or foreign matter falling upon it, and is self cleaning due to the movement of water flowing through it; and which will not wash out under the action of large amounts of water.

20 These and other objects and advantages of the invention will become apparent from the following specification which should be read with the understanding that the form, construction, and arrangement of the device as herein described may be varied, within the 25 limits of the claims hereto appended, without departing from the spirit of the invention as expressed in said claims.

A preferred embodiment of the invention will now be described fully with reference to 30 the accompanying drawings, wherein:—

Fig. 1 is a transverse section showing the device installed at the edge of a highway grade fill.

Fig. 2 is a front elevation of the device.

45 In the drawings, the reference numeral 1 designates a portion of a fill supporting a highway grade surface 2, and having a sloping side 3. My drain culvert comprises a cylindrical drum-like receiving head 4 formed 50 of corrugated sheet metal, preferably gal-

vanized iron or steel, and having closed ends, one of which is shown at 5. The front of the drum 4 has an inlet aperture 6, preferably rectangular, and at the rear is an outlet aperture 7 adapted for connection with a 55 tubular conduit 8, the latter being also preferably formed of corrugated sheet metal. An apron or bulkhead 9 is secured to the lower portion of the drum 4 and extends 60 downwardly therefrom.

In installing the device, the drum or head 4 is placed at the side of the highway 2, and at the upper edge of the fill, with the inlet aperture 6 facing the highway. The outlet conduit 8 extends downwardly as far as necessary upon the sloping side 3 of the fill. The drum 4 and the upper end of the conduit 8 are then covered with earth, as shown at 10, and this additional fill is extended longitudinally along the edge of the highway to 70 form a gutter 11 for the purpose of directing the water to the inlet 6 of the drum. The bulkhead 9 is buried in the main fill 1, and this together with the additional fill 10, holds 75 the device securely in position and prevents it from washing out.

It will be readily understood that rain water falling upon the highway 2 is directed by the gutter 11 to the inlet 6 of the drum or head 4, and flows into and through said drum 80 and out through the outlet 7 and the conduit 8, discharging at any suitable point, not shown, preferably at the bottom of the fill. Because of the cylindrical and corrugated construction of the head 4, it can be made 85 sufficiently rigid to prevent destruction or serious damage from being accidentally struck by the wheels of vehicles passing along the highway, and at the same time will not cause material damage to such wheels 90 striking it. The corrugated sheet metal construction, moreover, prevents the device from being damaged by the settling of the fill. The cylindrical form of the head 4 with the inlet 6 on the side prevents the device from being 95 clogged by leaves or other foreign material falling upon it, and also permits the water flowing through it to carry away any such foreign matter that may find entrance. The device is inconspicuous in appearance, can 100

be made, shipped and installed at a minimum cost, and can be easily taken up and moved to other locations, if desired.

Although it is not essential, I prefer to make the head 4 of a single sheet of cylindrically bent corrugated metal, with its ends separated to form the inlet aperture 6. The ends 5 are applied in any desired manner, and strips 12 are secured across the ends of the inlet 6, as shown, to assist in holding the head in cylindrical form.

A second bulkhead or flange 13 is preferably secured to the front of the head just above the inlet 6, and extends upwardly a short distance, in order to retain the earth at the top of the additional fill 10 and prevent it from falling in front of said head and obstructing the inlet.

I claim:

- 20 1. A drain culvert comprising a drum like head having an inlet at one side and an outlet, and a conduit connected with and leading away from said outlet.
- 25 2. A drain culvert comprising a drum like head formed of corrugated sheet metal and provided with an inlet at one side and a substantially opposite outlet, and a conduit connected with and leading away from said outlet.
- 30 3. A drain culvert comprising a drum like head forming a receiving chamber with an inlet at one side and an outlet, a conduit connected with and leading away from said outlet, and a bulkhead secured to the lower portion of said head and extending downwardly therefrom.
- 35 4. A drain culvert comprising a drum like head forming a receiving chamber and having closed ends and inlet and outlet apertures in its side walls, and a conduit connected with and leading away from said outlet.
- 40 5. A drain culvert comprising a drum like head forming a receiving chamber provided with an inlet on one side and an outlet, an exterior flange positioned above said inlet and extending upwardly therefrom, and a conduit connected with and leading away from said outlet.
- 45 6. A collecting head for drain culverts comprising a substantially cylindrical drum having an inlet on one side and a substantially opposite outlet, an exterior flange positioned above said inlet, and a bulkhead extending downwardly from the lower portion of said drum.

In testimony whereof I have signed my name to this specification.

ARTHUR R. HUTTON.
